SAMUEL TULLY WILLSON, OF BROOKLYN, NEW YORK.

FLUID-FUEL BURNER.

1,215,229.

Specification of Letters Patent.

Patented Feb. 6, 1917.

Application filed September 23, 1916. Serial No. 121,874.

To all whom it may concern:

Be it known that I, SAMUEL TULLY WILLSON, a citizen of the United States, residing at Brooklyn, in the county of Kings and 5 State of New York, have invented certain new and useful Improvements in Fluid-Fuel Burners; and I do hereby declare the following to be a full, clear, and exact description of the invention, such as will enable 10 others skilled in the art to which it app pertains to make and use the same.

My invention relates to fluid fuel burners, and more particularly to those for burning a mixture of gas and air above a dia 15 phragm or grid.

It is the object of my invention to provide a burner which will permit a wide range of adjustment in the amount of both the gas and the air or oxygen supplied, without 20 causing the flame to blow away from the burner or to flash back through the burner (back fire).

I prevent the flame blowing away by caus- 25 ing a portion of the gas and air to issue from the burner at a much lower velocity than the main body; and I prevent the flame from flashing back through the burner by either keeping the velocity of the mixture greater than the rate of flame propagation, 30 or keeping the temperature of the mixture within the burner below the ignition tem- perature, or both.

The burner consists of a shell whose wall is preferably thick, its upper portion having 35 an open discharge chamber and its lower portion inclosing a distributing chamber into which the gas and air are led from any suitable source; and a diaphragm or grid properly supported within the shell between 40 its upper and lower portions and made up of a multiplicity of small upright elements, of refractory material or otherwise, dis- posed in close contact with each other and with the wall of the shell. These elements 45 are non-angular and preferably round or cylindrical so as to leave interstices between them, and the elements may be short pins contacting with each other for perhaps two-thirds of their length and the remaining 50 third tapered upward to points. Other de- tails enter into the construction of the burner as set forth below. Reference is had to the accompanying drawings wherein:—

Figure 1 is a plan view and Fig. 2 a ver- 55 tical section of one type of this burner.

Figs. 3, 4 and 5 are enlarged details of pins.

Figs. 6, 7 and 8 are diagrammatic views of supports.

Fig. 9 is a sectional detail showing one means for mounting the support in the shell.

The shell 1 is tubular, stands on a vertical axis, has a rather thick wall threaded at its lower end as at 2 for connection with any suitable source through which is supplied the gas and the air, and internally its lower portion contains a distributing (or in some cases a mixing) chamber 3. Its upper end is shown as open at 5, and below the same stands the grid yet to be described, and which separates the chamber 3 from the upper portion of the shell which might be called the combustion or discharge chamber 4. In the construction shown in Figs. 1 and 2 the shell is round or cylindrical externally, but it is hexagonal internally as at 6.

The two so-called chambers are separated by a rather thick diaphragm, or more properly a grid, which is made up of a number of relatively short elements 7, non-angular and preferably cylindrical and of metal or of refractory material such as fire clay, magnesia, etc. Between the elements themselves and between them and the wall of the shell are interstices 8 open at their upper and lower ends. In the type of my invention shown in Fig. 6 is disclosed parallel rows of these elements standing in close contact with each other and in close contact with those in contiguous rows, or checked both ways across the shell. In the type shown in Fig. 7 the elements are disposed in parallel rows, but staggered. In Fig. 1 the entire cluster of elements makes up a grid of hexagonal contour. Here also the elements although staggered stand in close contact with each other and produce triangular interstices between them, and the outermost elements stand in close contact with the wall of the shell.

If the elements are of metal they may be wedged into position by being pressed or driven into place with such force that no extraneous means is necessary to hold them, and the absence of such extraneous supporting means leaves the interstices unimpeded. If the elements are of refractory material they may be supported on a foraminous sheet provided the latter forms no impedance to

the flow of fluid through the grid. This foraminous support may be a wire screen 10 suitably mounted within the shell, as perhaps by resting on a shoulder 11 therein as seen in Fig. 9, but its meshes should be square as seen in Fig. 6 if the elements are checked both ways, or should be of diamond shape as seen in Fig. 7 if the elements are staggered. I reserve the broadest latitude 10 in this respect, and the foraminous support might even be parallel wires as seen at Fig. 8; but in any case it is desirable that the openings in the support register well with and are perhaps larger than the interstices 8 15 between the elements 7.

While the bodies of the elements are preferably cylindrical and in any event must stand in close contact with each other, I prefer that their upper ends shall be reduced 20 as has been stated. Such ends may be made conical as seen at 14 in Fig. 4, the walls of the cone may be dished slightly as seen at 15 in Fig. 5, or the walls of the cone may bulge slightly as seen at 13 in Fig. 3— 25 thereby making the points parabolic which is the structure I prefer; but in this respect also I reserve the widest latitude, so long as the upper ends of the elements are tapered, and it may not even be necessary to 30 taper them completely to the points as shown at 16. Whatever the form of taper, it will be clear that the result is that the interstices between elements are separated from each other and of one size and shape 35 throughout the length of the bodies of the elements, and at the line where these bodies merge into the tapering ends the interstices expand in size and are in communication with each other—the communication being 40 slight at first and growing more ample toward the surface of the grid. If the upper ends are carried to points 16 as shown, in the plane of all the points it will be clear that the interstices have expanded in size to 45 such an extent that they merge into each other and into the chamber 4 or in other words the walls of the interstices have entirely disappeared. While such enlargement of the interstices is gradual in any 50 event, it is constant if the upper ends of the elements are conical as seen in Fig. 4, or if said ends have the shape shown in Fig. 13 the enlargement of the interstices is slight at first and grows gradually more rapid up 55 to the plane of the face of the grid. It is quite within the spirit of my invention that the different elements at different parts of the grid might be variously tapered, but this suggestion will not need illustration.

60 In the use of this burner the fluid fuel or gas and the air to be mixed therewith are supplied to the shell at its inlet end, which is that end shown as threaded, and it flows into the chamber 3 where it is preheated

and expanded by the warmth of the wall of 65 the shell. Passing upward from this chamber, it flows through the grid, and in any construction it passes through the interstices thereof. While doing so, that portion of 70 each subdivision of the mixture which flows along the corners or angles of the interstices is slightly retarded, whereas the remainder which might be said to flow along the axes thereof is not retarded to such an extent and therefore moves more rapidly. The result is that when the mixture is lighted 75 along the top of the grid, the flame is not blown away from the grid by the velocity with which the mixture passes through it. On the contrary, the flame will closely overlie the surface of the grid, even though the admission of air and gas is adjusted through a wide range. I consider the proper adjustment to be such that the velocity of the mixture shall be slightly greater than the 80 rate of flame propagation. This provides one reason for preventing the flame from flashing back through the grid into the mixing chamber, which is so common in burners of this type. The elements soon become 85 heated, and as they are in close contact with each other and all of one material the heat is conveyed from one to another and is spread over the grid uniformly. As the outermost elements are in close contact with 90 the wall of the shell, some of this heat is communicated to such wall which a little lower surrounds the chamber 3, and the result is that the mixture therein is preheated 95 as above described; and yet the heat below 100 the grid is always lower than that of ignition temperature, which is another reason for preventing backfiring.

With the upper ends of the elements tapered and perhaps pointed as shown, the mixture after flowing through the interstices may expand between the points, and the result is that as it reaches the plane in which combustion is maintained it is flowing less rapidly than lower down within the interstices. 110 This causes combustion to take place on the very surface of the grid, so that the tips of the points become highly heated and incandescent. While I prefer to have the elements round or cylindrical as shown, I 115 would always have them non-angular so as to leave interstices between them, and the interstices should have angles to retard the flow of some portion of the stream of mixture passing through them.

120 What I claim is:

1. A burner comprising a shell and a cluster of upright non-angular elements standing in said shell parallel to its axis in close contact with each other and extending uninterruptedly across it, the outermost elements being in close contact with said wall so as to communicate their heat thereto, said 125

elements constructed to provide a series of ducts each outwardly flaring at their outer ends.

2. In a burner, a shell and a grid composed of bars parallel to the axis of the shell, each having differential diameters at different points longitudinally and standing parallel in close contact with each other and extending uninterruptedly across the interior of the shell.

3. In a burner, a tubular shell and a grid across it between its upper and lower ends composed of longitudinally tapering elements of refractory material disposed parallel to the shell axis so as to produce interstices.

4. A burner comprising a shell and a grid arranged across the interior thereof and made up of a number of elements arranged parallel to the axis of the shell forming interstices and standing in close contact with each other, said elements having their upper ends tapered.

5. A burner comprising an upright tubular shell, and a grid supported across the interior thereof and made up of a number of individual cylindrical elements standing in close contact with each other and having their upper ends tapered to points.

6. A gas burner having a grid or diaphragm whose body is pierced by a number of ducts each terminating with a flaring mouth, all of which merge into one in a common plane at the surface of the grid.

7. A combustion plate consisting of a cluster of cylindrical elements with their axes perpendicular to the plate and having the ends which form one side of the plate tapered.

8. A burner comprising a tubular shell,

a grid across the interior thereof and made up of a number of individual non-angular elements of refractory material in close contact with each other and having their upper ends tapered, and a support for the grid 45 consisting of a foraminous sheet mounted within the shell.

9. A burner comprising an upright shell having an internal shoulder between its ends, a foraminous metal support resting on the shoulder, and a grid resting on the support and having upright openings registering at one end with those in the support and each opening flaring outwardly at its other end and all merging together. 55

10. A burner comprising an upright shell, a support of mesh metal fabric across it, and a grid composed of cylindrical elements whose bodies are in close contact with each other and disposed in checked rows along 60 the strands of said fabric with the interstices between them registering with the openings in said fabric, and whose upper ends are tapered upward to a plane below the upper end of the shell. 65

11. A burner comprising a tubular shell, a grid across the interior thereof and made up of a number of individual elements parallel to the axis of the shell forming interstices and having their upper ends 70 tapered, and a support for the grid.

12. A chamber having a combustion plate across one end, said combustion plate being made up of a series of refractory elements cylindrical in form and in close proximity to each other and with their outer ends tapered. 75

In testimony whereof I affix my signature.

SAMUEL TULLY WILLSON.
